[57] **CLAIM**

The ornamental design for a printer inksheet, as shown and described.

DESCRIPTION

FIG. 1 is a top plan view of a printer sheet, showing our new design;

FIG. 2 is a partial enlarged view thereof of area 2 shown in FIG. 1; and,

FIG. 3 is a referential front, top and right side perspective view thereof.

The broken lines shown in FIG. 3 are for illustrative purposes only and form no part of the claimed invention.

1 Claim, 3 Drawing Sheets

FIG. 1

FIG. 2

FIG. 3
